UNITED STATES PATENT OFFICE.

DAVID J. SIMPSON, OF CHICAGO, ILLINOIS, ASSIGNOR TO NOAH STEINER AMSTUTZ,
OF VALPARAISO, INDIANA.

STEEL-TREATMENT APPARATUS.

1,351,495.

Specification of Letters Patent. Patented Aug. 31, 1920.

Application filed April 5, 1915, Serial No. 19,311. Renewed December 29, 1919. Serial No. 348,050.

To all whom it may concern:

Be it known that I, DAVID J. SIMPSON, citizen of the United States, residing at Chicago, in the county of Cook and State of Illinois, have invented certain new and useful Improvements in Steel-Treatment Apparatus, of which the following is a specification.

My invention relates to improvements in steel treatment apparatus and it consists more especially of the features hereinafter pointed out in the annexed claims.

The purpose of my invention is to provide apparatus for the treatment of steel which will give superior results to those obtained by means of ordinary quenching methods; to provide means for controllably hastening the cooling of the heat treated steel; to handle a large quantity of material at one time; to effect economies in production, insure uniformity of results, and simplify the handling of bulky material; and to provide means for efficiently heat treating the steel before cooling the same.

With these and other ends in view I illustrate in the accompanying drawings such instances of adaptation as will disclose the broad features without limiting myself to the specific details shown.

Figure 1— is a diagrammatic elevation of a part of a heat treating installation.

Fig. 2— is an end elevation partly diagrammatic of the cooling apparatus shown in Fig. 1.

Fig. 3— is a diagrammatic elevation of a complete installation.

Fig. 4— is a transverse elevation of an outlet chamber.

Fig. 5— is a cross section elevation of a heating furnace.

Fig. 6— is a plan view partly in section of Fig. 5.

Fig. 7— is an elevation of manually operated distance blocks.

Fig. 8— is a side elevation of Fig. 7.

Fig. 9— is an elevation of sectional hoods.

Fig. 10— is a plan view of Fig. 4.

Fig. 11 is a plan view showing the transverse relation of the tracks, etc.

Fig. 12 is a detail elevation showing a removable rail partly in the furnace.

Fig. 13 is a detailed elevation of the part of Fig. 2 showing a lifting eccentric of the

buggy placed outside of the range of the shaft bearing.

55

The steel after having been heated as a billet and hammered into shape is allowed to cool on suitable racks 18 where the axles are stored preparatory to being reheated and treated in carrying out my invention.

60

The reheating is done in furnace 1 in any desired manner so long as provision is made to control the intensity and distribution of the heat. This may comprise any desired system of dampers etc. In the instance

65

shown in Figs. 11 and 12 the floor of the heating chamber 3, outside the range of the axles has two lengthwise channels 73 which may be lined with fireproof cement if found desirable. Removable rails 78 are placed in these channels, after the heating is complete and doors 6 are opened, with the leading-in end alined with the buggy tracks 66. A transfer buggy 22 is quickly run onto rails

70

78 so that a lifting channel 74 will have its lower flange 75 under each end of axles 2 to be raised by eccentrics on shaft 76 and the axles carried to the cooling chamber. Owing to the prolonged intense heat track rails

75

for the buggy cannot be permanently placed in the furnace. Skids 77 on which the axles rest while being heated are not fastened to the floor so are free to twist sidewise without hindrance. When rails 78 are no longer

80

usable new ones can be substituted. The skids 77 may approximately line up with racks 18 and rails 19 and the support rails 48 of the cooling chamber while the removable rails 78 are self-alined with buggy tracks 66 as stated. The exact spacing of the axles 2 on the skids 77 is im-

85

material, in fact not practical as the axles are rolled into the furnace from racks 18 over short well known bridging rails by hand. Certain special features which relate to the details of the transferring buggy etc., its loading, unloading etc., are made the subject of a separate application filed April

90

5, 1915 Ser. #19,312.

100

The materials to be treated may be placed on suitable supports 77 slightly above the furnace floor to allow for underneath circulation. In the instance of adaptation shown the axles 2 are placed on longitudinal bars 77, but with materials of other shapes they may be placed in any kind of

105

suitable holder adapted to easy transfer. The heating chamber 3 has bridge walls 4 and 5 to form the lengthwise side walls and sliding doors 6 at each end. These are counterbalanced in any suitable manner.

The combustion chamber 7 is separated from the heating chamber 3 by bridge wall 4. An opening 8 below the roof 9 forms a passage way between them and a similar opening 10 above bridge wall 5 leads the heat to a distributing chamber 11 from where passages 12 formed in the floor of the furnace lead to lengthwise passage 13 and by a common return 14 to the stack 15. Dampers 16 attached to external levers 17 control passages or flues 12 so as to regulate the heat of different portions of the furnace as may be required. The volume of heat is controlled by the quantity of fuel used and the regulation of the drafts in the usual manner.

The steel is first slowly heated to the required low heat according to its percentage of carbon. It is then held for a short time without change, after which it is subjected to the required high heat corresponding to its given carbon content, then as quickly as possible transferred to the cooling chamber where the heat rapidly radiates. From this it is seen that both the heating and cooling must be carefully controlled. Indicating or recording pyrometers should be used in all cases so as to be able to exactly note the conditions at any step in the treatment and suitable inspection windows some of which may be made to serve for the introduction of the pyrometer points should be provided.

The steel from the hammers is stored on racks or horses at 18 from where the furnace 1 is charged in any desired manner. At this point buggy rails 78 shown on Fig. 12 are stored with one end supported by a suitable hoist traversable on an overhead runway. The track rails when made removable are provided with wheels at the ends nearest the furnace as shown in Fig. 12. They run in the channels 73 and when through the furnace they engage suitable guides which lead them into alignment with the tracks 66 lying between the furnace and the cooling chamber where they are rigidly, yet removably held in any desired manner.

A suitable elevated structure 20 reaches from the cooling chamber to storage space 18 so that any steel which may require re-treatment can be taken from the cooling chamber and stored on tracks 19 from where it can be lifted over the furnace by overhead crane 21 to the racks 18 without interfering with another batch of steel that may be under treatment in the furnace.

As soon as a "charge" has gone through the required heating the doors 6 are opened, and when removable tracks 78 are used they are quickly inserted and the buggy 22 moved

on to the same and into the furnace so as to leave its motor 23 on the outside. Should it however be found desirable it is probable the motor could be sufficiently insulated against heat to pass through the furnace. Under ordinary circumstances the buggy need not pass through the furnace at all. The propelling motor 23 also serves to raise all the pieces simultaneously from the furnace floor the required distance to clear any obstruction through a rotation of eccentric shafts 76 placed near each end of the axles. From the shafts 76 channels 74 depend so as to have their lower flanges underneath all the axles. The buggy 22 rapidly carries the material to the cooling chamber, quickly lowers it to the supporting rails 48 and passes out at the other end. The hood 24 is lowered into the water tank below the rails and the cooling part of the operation is then carried out by forcing air or other gases at the necessary temperature into the chamber and controlling the outlets by means of suitably placed dampers 61.

Hood 24 is supported on counter balancing weighted cables from elevated structure 25 so that it may be easily raised and lowered. To quickly effect this, racks 26 are fastened near each corner of the hood of the required length. These mesh with gears 27 suitably supported on projecting brackets 28 placed on each side of the hood. In order that the hood may be raised from either side a shaft is provided for a pair of gears 27 and on this suitable sprocket wheels may be placed. Two of these, one on each shaft, are connected with a crossed sprocket chain 29 so as to cause both shafts, attached gears 27 and racks 26 to move in unison. The shafts may be operated by hand or motor as desired. Sprocket chains 30 lead from the gear shafts to suitable cranked wheels 31 placed at each side of the hood and attached to the supporting posts of elevated structure 25 so as to permit of hand manipulation. The motor 32 may be connected to either one of wheels 31 so as to raise and lower hood 24 by power if required.

The hood 24 has a perforated partition 33 horizontally secured therein below the cover thereof thus serving to evenly distribute the cooling agent which may be brought in by pipe 34 under any required temperature and pressure. A deflector may be placed at 35 to direct the cooling media toward the ends of the hood and a damper 36 is placed above the deflector so as to confine the heat to either end of the hood. Transverse partition 37 helps to isolate the ends from each other if desired. When both ends of the hood are to be used damper 36 would be placed in a mid position leaving passage ways open to both sides of the deflector 35.

The cooling agent is brought to pipe 34 by means of a suitably pivoted telescopic pipe 130

38 connected to a main supply 39 in any desired manner. If needed the pipe 38 may be counterweighted. As the hood rises or falls pipe 38 will retain connection with 39 5 and 34. In order to prevent hood 24 from swaying I may place guide bars 40 on either side having suitable wheels to engage both faces of the flanges of adjacent supporting posts 41. Suitable inspection windows 42 10 and pyrometer openings 43 are provided. Any desired form of limit stop may be used to prevent hood 24 from engaging the floor of the water-sealing tank 44. This may comprise a number of corner blocks placed on 15 the floor of the proper height to leave the hood rest thereon.

Tank 44 has inlet pipe 46 and outlet pipe 47 which keep the water level uniform and also provide for continuous circulation. 20 Within this tank a given distance away from the walls on all sides a suitable track comprising rails 48 and pillars 49 is constructed on which to place the steel to be cooled. If the steel is brought in by buggy 25 22 solidly attached distance blocks 50 may be fastened on top of the rail head by rivets or otherwise, thus insuring that the axles are properly spaced with respect to the air outlet chambers 58 suspended from the 30 tracks. If the axles as deposited by the buggy should happen to rest on the top of any of the distance blocks 50 they are shifted into position between block ends by pinch bars, manipulated by hand, before the hood 35 is lowered. In the case of other forms of materials, they may be placed in suitable metal baskets that can be similarly spaced on the tracks or any other form of container may be used. Should the steel however be 40 rolled in by hand other distancing arrangements would need to be provided. These are shown in Figs. 8 and 9. They comprise swinging blocks 52 suitably pivoted to a "fish" plate 55 attached to the web and resting on the side flange of the rail. One end of each block has a depending arm to which a connecting rod 53 is attached. A suitable pendant 54 enables an operator to move the same with a hook in either direction, to 45 50 move the block into place or remove it so as to leave the tracks free for the passage of the axles. Parts 52 and 54 are locked together by bale 67 pivoted to 54 so that blocks 52 will remain on rails 48.

55 Should it be found desirable to treat smaller groups of axles or material containers, I may use the expedient shown in Fig. 9 wherein the hood is divided into independent sections, in which case the tracks, 60 65 48 would have to be similarly separated so as to allow the adjacent hood walls to pass into the water of the tank. Under these conditions the discontinuous tracks would have to be made so as to automatically or otherwise restore their continuity when

needed to roll axles on or off the tracks. One way in which this may be accomplished (see Fig. 9) is to counterweight swinging bars 56 attached to each other by a transverse shaft and normally held "open" by a 70 suitably placed counterweight 57. If the materials are to be moved both ways on the track special manually operated track gates may be provided so as to operate in any desired manner. 75

The passing of the cooling agent from hood 24 may be provided for as follows, a series of detachable chambers 58 are suspended from rails 48 by suitable brackets. They are water proof and are connected 80 with a header 59 which leads to outlet pipe 60. Suitable dampers 61 are pivoted at 62 so as to swing horizontally and they are so shaped as to open more rapidly at the centers than at the ends. Rock shafts 63 are 85 pivoted on both sides near the bottom. To these, rock arms 64 are secured so that pins projecting from their free ends pass through openings of dampers 61. Hand levers 65 are attached to both ends of rock shafts 63 90 and are accessible from the outside of the hood even when entirely lowered. Shafts 63 pass through under the bottom edges of the hood consequently there is no interference between them and the dampers 61 may 95 be moved independently of each other from both sides of the hood 24.

On each side of tank 44 buggy tracks 66 are placed and suitable trolley wires may be carried outside of the line of hood movement and insulated in any desired manner. The controlling switch and rheostats, etc., being at any desired point of control. 100

With the apparatus instanced in the drawing and description, or its substantial equivalent I am able to secure a greater uniformity of product than has hitherto been attainable, with the highest elastic limit, tensile strength, percentage of elongation and reduction of area, securing the finest granular structure of the steel without sacrificing toughness and ductility. The results are far superior to those secured with quenching processes because the sudden cooling of a hot section of steel will contract the outside inwardly encountering the expanding stresses of the inner layer of material thus producing dangerous internal strains which are liable to jeopardize human lives and incur serious material damages. 105 110 115

I may use any kind of cooling agent that will give me the desired result without destroying the good quality secured by the staged heat treatments. This may be air at various temperatures, dry steam or any 120 125 other media which does not require bodily quenching.

In case the materials are conveyed to and from the cooling chamber exclusively by means of the buggy 22, the axle supporting 130

- rails 48 would not extend beyond the pillars 49 thus leaving an unobstructed space for the hood to drop into. Should however recourse be had to hand transference of the 5 axles then such rails would need to have automatically raised bridges which may be formed by hinged track sections 68 attached to cables 69 which pass over sheaves 70, through eyes 71 fastened to hood 24 ending 10 with counterweights 72. The slack on the descent of the hood is first taken up and then the track sections 68 are raised before the hood reaches them. Any other expedient such as bridges 56, etc., may be used.
15. What I claim is,
1. A suitable furnace, means for supplying heat thereto in a controllable manner, a cooling device, suitable trackages therebetween, means for transferring material from 20 one to the other, means for hermetically sealing the cooling device, means for causing the rapid traverse of a cooling medium therethrough, and means for varying such traverse in different parts of said device.
  25. 2. A cooling chamber comprising a movable hood, a water seal tank therefor, a suitable isolated support within the tank, a flexible conduit leading to the hood, a series of outlets attached to said support, and means for controlling the inlet and outlets thereof.
  30. 3. A suitable furnace, oppositely placed openings therefor constituting charging and delivery ends, a storage space adjacent each end, a cooling chamber beyond one of the storage spaces, a conveyer traversing the furnace, the inter-space and the chamber, and a second conveyer adapted to traverse over both storage spaces and the furnace on a different plane whereby materials requiring reheating may be delivered from the chamber to the space adjacent the charging end of the furnace without interfering with materials being heated in said furnace 40 and their subsequent transfer to the cooling chamber.
  35. 4. A cooling chamber comprising a suitable tank or container, means for maintaining a sealing medium in circulation therein, means for holding such medium at a critical level, a support within the tank rising above the sealing liquid, a clear space all around said support, a hood, means for supporting the same, means for imparting movement thereto so that its depending side and end walls may pass into the clear space of the tank, and means for supplying a cooling agent to the hood, means for variably controlling the exit of said agent whereby 50 heated materials may be cooled in a controllable manner.
  55. 5. A cooling chamber comprising a suitable tank, a water circulating system in connection therewith, a suitable hood adapted to be lowered into the tank with

its bottom edges below the water line, a stationary support within the hood but independent thereof, the said support extending above the water line and a traversing buggy adapted to move onto and off from 70 the support.

6. A cooling chamber comprising a suitable tank, means for maintaining circulating water therein, a support extending above the water level, a series of exit chambers 75 suspended therefrom, a common outlet for the same, a vertically movable hood adapted to inclose the support and the exits, suitable independent dampers for the several exit chambers, and means for operating said 80 dampers when the hood is lowered.

7. An inclosing hood, a water holding tank, means for lowering and raising the hood within and above the tank, a suitable inlet to the top of the hood, a deflector adjacent the entrance, a perforated partition extending across the hood, and means for directing movement of a traversing media to either or both ends of the hood. 85

8. An inclosing supporting structure 90 divided into one or more sections, an independent inclosure for each simultaneously or independently operable, means for imparting vertical movement thereto, independent inlets to each inclosure and an outlet common to all. 95

9. A water containing tank, a series of separate supports therein, a plurality of hoods movable within and above the tank adapted to independently inclose the supports, and means for connecting the supports to each other when the hoods are raised. 100

10. A suitable tank, a support therein comprising suitable bars or rails, and pillars therefor, movable and independently operable distance blocks adapted to rest on the rails, and means for operating them in pairs from either side of the tank. 105

11. A furnace, a treatment chamber, 110 transfer trackage therebetween and external of the said chamber, isolated supports within the chamber, a movable hood to inclose the same, tracks on the supports independent of the transfer tracks, an overhead traversing conveyer, means for supporting the same on a different plane and independently of the transfer tracks, removable rails connecting the tracks with the inside of the furnace, a portable buggy 115 traversable on the rails and tracks, and means for propelling the same to discharge the furnace and transfer the materials to the treatment chamber and after treatment therein to remove the same therefrom. 120

12. A furnace, a separate treatment chamber, transfer trackage adapted to serve the furnace and the chamber, a movable hood to isolate said chamber, an air supply to the hood, an air exit from the chamber, sup- 125

ports therein to hold materials, tracks on the supports independent of the transfer trackage, a buggy traversable on the latter, means for propelling the same, and stationary means for controlling the movement of the buggy.

13. A cooling chamber comprising a tank, an isolated support therein, a movable hood to inclose the support, an air inlet to the hood, an air outlet from the tank, trackage 10 on the support, independent trackage external of the hood and tank, a buggy traversable on the external tracks, and means for propelling the same.

14. In steel treatment apparatus, a treatment chamber comprising a tank, adapted 15 to hold a liquid, isolated supports therein, tracks on supports for holding the articles to be treated, a movable hood to inclose the 20 tracks and supports, an air inlet to the hood,

an air exit from the tank, independent trackage external of the hood and tank, a buggy traversable on the external tracks to bring in and remove the articles, and means for propelling the buggy.

15. A cooling chamber comprising a movable hood and a tank therefor, trackage leading to supports in the tank thereover the supports and from the tank, jointed sections in said tracks where they approach 25 and recede from the tank, a means adapted to raise said sections before the hood is lowered and vice versa lower the same after the hood has been raised.

In testimony whereof I affix my signature in presence of two witnesses.

DAVID J. SIMPSON.
